STRIP FEED DRIVING MECHANISM FOR AUTOGRAPHIC REGISTERS

Filed July 29, 1935

UNITED STATES PATENT OFFICE

2,092,260

STRIP FEED DRIVING MECHANISM FOR AUTOGRAPHIC REGISTERS

William A. Pringle, Niagara Falls, N. Y., assignor
to American Sales Book Company Inc., Niagara
Falls, N. Y., a corporation of Delaware

Application July 29, 1935, Serial No. 33,648

13 Claims. (Cl. 74—548)

This invention relates to improvements in writing machines, such as autographic registers and the like, and more particularly to improvements in the record strip feeding mechanism for machines of this character.

It is a general object of the invention to provide for machines of the class mentioned an improved strip feeding mechanism which is entirely enclosed and concealed within the casing of the machine so as to avoid parts of the mechanism projecting beyond or outside of the bounds of the casing, and at the same time providing a convenient means for operating the feed mechanism.

Another object is to provide for machines of the class mentioned an improved attaching device for the operating handle, whereby said handle may be quickly and easily attached to the feeding mechanism, or removed from attached position, without the necessity of opening the casing, while at the same time only the handle and its operative connection are exposed to the exterior of the casing.

Another object of the invention is to provide an improved attaching device for attaching the operating handle to the feeding mechanism including improved means for facilitating placement of the handle in operative position, and having an improved attaching device permanently attached in position on the handle.

Other objects of the invention will be in part pointed out in the following detailed description of an illustrative but preferred embodiment of the invention, and will be in part obvious in connection therewith.

The invention accordingly comprises the features of construction, combination of elements and arrangement of parts which will be exemplified in the construction hereinafter set forth, and the scope of the application of which will be indicated in the claims.

For a more complete disclosure of the nature and objects of the invention, reference is had to the following detailed description and to the accompanying drawing, in which:

Fig. 1 is a side elevation of a writing machine of the autographic register type equipped with the invention, and

Fig. 2 is an enlarged vertical transverse section of Fig. 1, taken substantially on the axis of the feed shaft.

Although the improved feeding mechanism may be used in connection with various machines, it is herein disclosed as installed in a record or writing machine of the autographic

register type, of the general nature disclosed in Patent No. 1,827,745, L. F. Hagemann, dated October 20, 1931. As in the Hagemann patent, the feeding mechanism is operated by a handle of the reciprocating lever type, but it will be obvious that other types of operating means are applicable.

As shown in the drawing, there is a supporting frame 5 for the feed assembly mounted within a casing 6 which provides a housing for the operative elements. This frame may be mounted in the casing for installation or removal as a unit, as by means of supporting blocks 7 attached to the bottom of the casing and to which the side frame members of the frame may be detachably connected in any convenient manner. A platen (not shown) may be provided as in the Hagemann patent mentioned for supporting the record strips in position for the reception of inscriptions, and these strips are fed forwardly from a supply into writing position by means of the feeding mechanism. The frame 5 is provided with transversely aligned bearings 8 rotatably supporting the feed shaft 9 which carries spaced feed disks 10 cooperating with a feed roll 11 mounted in a feed roll carrier or housing 12 and yielding urged into gripping relation with the disks by means of springs 13. By means of this arrangement, the work webs or record strips will be gripped between the feed disks and the feed roll and thus fed forwardly upon rotation of the feed shaft in a manner fully disclosed in the Hagemann patent mentioned.

Driving mechanism for the strip feed disks 10 includes a toothed driving element or sector 35 14 having a hub 15 apertured for receiving a stub shaft 16 attached to the frame for rotatably mounting the driving sector. The teeth of the driving member 14 mesh with those of a pinion 17 rotatably mounted on the extending end of the shaft 9 and having driving connection with the driving member 18 connected to the shaft 9. The pinion 17, as in the Hagemann patent referred to, is coupled to the driving member 18 so as to drive the feed disks 10 forwardly in strip feeding direction. After each feed stroke of the pinion 17 to rotate the feed disks forwardly, said pinion is reversely rotated idly to its initial position from which it starts for the next successive strip feeding cycle. It will be observed that the entire strip feeding mechanism, including the driving sector 14 and the stub shaft 16, is disposed wholly within the walls of the casing 6 so that no part of said mechanism protrudes beyond the walls of the casing. Not only does this

arrangement provide for an
1
beauty and symmetry are unmarred by projecting
parts, but it provides for the convenient instal-
lation of the entire feeding mechanism in the
casing and for a simple and easy removal thereof
from the casing. Thus the frame 5 with the
assembled feeding mechanism may be lowered
from above into the casing and attached in po-
sition to the supporting blocks 7. The mecha-
nism then is in its operative position ready to
receive the driving element which is attached in
driving position from the exterior of the casing,
as fully described below.

15 In the embodiment of the invention herein
disclosed, the feeding mechanism is driven by
means of a driving arm 19 of the reciprocating
lever type. This driving lever or crank 19 is
provided with a handle and has a driving con-
nection with the hub 15 of the driving sector 14.
It will be understood, however, that a different
type of driving member may be substituted for
the crank 19. At its lower or axial end the crank
19 is provided with a hub 20 connected in any
desired manner and having a peripheral groove
21 preferably extending entirely around the hub
so as to provide an inwardly disposed shoulder.
An internally threaded sleeve nut 22 is rotat-
ably mounted upon and telescopically encloses
30 the hub 20 and is provided with an outwardly
disposed annular retaining flange 23 extending
into the peripheral groove 21 whereby the nut
is permanently retained in position upon the hub
but is rotatable thereon. At its inner face the
35 hub 20 is formed with inwardly projecting lugs
24 positioned for entering into slots 25 cut in the
outer face of the sector hub 15. This slotting
of the hub 15 provides lugs on said hub arranged
40 to contact with the lugs 24 so as to lock the two
hubs 15 and 20 together against relative rotation
when in assembled position. The outer end or
projection of the hub 15 is externally threaded
45 for receiving the threads of the sleeve nut 22,
thus to retain the lever hub 20 in assembled re-
lationship with the sector hub 15.

In order to facilitate the assembly and at-
tachment of the crank arm in operative position
upon the driving sector 14, a guiding and sup-
porting device is provided. In the embodiment
50 shown this is in the form of a guiding and sup-
porting pin 26 which is securely attached in axial
position upon the lever hub 20 extending in-
wardly therefrom. This pin is positioned for
55 entry into a guideway formed in the frame of
the machine. As shown, this guideway is formed
by an axially disposed bore or aperture 27 in the
supporting stub shaft 16.

When the feeding mechanism is installed in
operative position in the casing, the sector hub 15
60 is positioned adjacent to and directly opposite to
an aperture 28 formed in the casing 6. The hub
15, however, is positioned wholly within the cas-
ing as above mentioned, so that there are no
projecting parts. This arrangement, however,
65 does not interfere with the attachment of the
driving lever 19 in operative position upon the
sector hub 15, and in fact the driving lever may
be quickly and easily attached by virtue of the
assembly auxiliary described. Thus, in assem-
70 bling the driving lever, the guiding and support-
ing pin 26 is first inserted into the aperture or
guideway 27, whereupon the driving lever is slid
inwardly into assembled relation with the lugs of
the hub 20 in engagement with those of the hub
75 15. When the crank arm is thus slid inwardly

As the ^{2,055,500} ₁
assembled sleeve nut 22 is grasped from
with the shoulders ¹
the hub 20 in its condensing position with
with reference to the hub 15. ¹
that the sleeve nut 22, in its final ¹
substantially as shown in Fig. 2, is located direc-
in the casing opening 28 so that the nut is ac-
cessible for operation from the exterior. While
this nut is preferably cylindrical in external con-
tour, as shown, its outwardly exposed periphery
may be knurled so as to be easily grasped for
turning it in its attaching or releasing move-
ments. When thus positioned, the sleeve nut
substantially fills the aperture 28 at all times,
thus avoiding gapping and unsightly openings in
the casing. The sleeve nut 22 may, as shown, be
conveniently held in operative position upon the
hub 20 by attaching the arm 19 in position upon
the hub after the nut has been assembled there-
on. By this means, together with the groove 21
and the flange 23 on the sleeve nut, said nut is
interlocked with the hub 20 in operative posi-
tion thereon. The crank arm when thus as-
sembled is effective for transmitting energy to
the strip feeding mechanism, and is effectively
retained in operative position and conveniently
assembled and disassembled by means of the im-
proved arrangement of parts described.

Since certain changes may be made in the
above construction and different embodiments of
the invention could be made without departing
from the scope thereof, it is intended that all
matter contained in the above description or
shown in the accompanying drawing shall be in-
terpreted as illustrative and not in a limiting
sense.

Having described my invention, what I claim
as new and desire to secure by Letters Patent is:

1. In a machine of the character described, in
combination, mechanism including a rotary driv-
ing member, a frame supporting said mech-
anism, a casing within which said frame and said
driving member are positioned, said casing hav-
ing an opening adjacent to said driving member
which latter is positioned wholly within the cas-
ing, an operating handle outside of said casing,
attaching connections mounted on said handle
and insertable through said casing opening into
connected relation with the driving member for
attaching the handle to said driving member for
operation of the latter, and a threaded sleeve
nut permanently rotatably attached to said han-
dle and cooperating with said driving member
to hold the handle in operative driving position
thereon.

2. In a machine of the character described, in
combination, mechanism including a rotary driv-
ing member, a frame supporting said mechanism,
a casing within which said frame and said driv-
ing member are positioned, said casing having an
opening adjacent to said driving member which
latter is positioned wholly within the casing, an
operating handle outside of said casing, attach-
ing connections mounted on said handle and in-
sertable through said casing opening into con-
nected relation with the driving member for at-
taching the handle to said driving member for
operation of the latter, a threaded sleeve nut
having a permanent interlocking connection to
said handle and cooperating with said driving
member to hold the handle in operative driving

position thereon, said sleeve nut extending through said casing opening and having its outer surface exposed exteriorly of the casing for operative access.

5 3. In a machine of the character described, in combination, mechanism including a rotary driving member, a frame supporting said mechanism, a casing within which said frame and said driving member are positioned, said casing having an opening adjacent to said driving member which latter is positioned wholly within the casing, an operating handle outside of said casing, a supporting and centering pin carried by said handle coaxially therewith for extending through 10 said casing opening into connected relation with the driving member and into supporting cooperation with said frame, and a threaded sleeve nut permanently rotatably attached to said handle and telescopically enclosing a part thereof 15 and cooperating with said driving member to hold the handle in operative position thereon.

4. In a machine of the character described, in combination, mechanism including a rotary driving member, a frame supporting said mechanism, a casing within which said frame and said driving member are positioned, said casing having an opening adjacent to said driving member which latter is positioned wholly within the casing, an operating handle outside of said casing, a supporting and centering pin fixed to said handle at the axis of rotation thereof for extending through said casing opening into supporting cooperation with said frame, and a threaded sleeve nut permanently rotatably attached to said handle and cooperating with said driving member to hold the handle in operative driving position thereon, said sleeve nut extending through said casing opening and having its outer surface exposed exteriorly of the casing for operative access.

40 5. In a machine of the character described, in combination, mechanism including a rotary driving member, an operating handle for said driving member, a supporting and centering pin carried by said handle coaxially with the latter for handle-supporting cooperation with said frame, a hub attached to said handle and having a peripheral groove, and a threaded sleeve nut rotatably mounted on said hub and having a retaining flange positioned in said groove and threaded 50 to said driving member to hold the handle in operative position thereon.

6. In a machine of the character described, in combination, mechanism including a rotary driving member, a frame supporting said mechanism, a casing within which said frame and said driving member are positioned, said casing having an opening adjacent to said driving member which latter is positioned wholly within the casing, an operating handle outside of said casing, attaching connections mounted on said handle and insertable through said casing opening for attaching the handle to said driving member for operation of the latter, a stub shaft mounted on said frame and having an axially disposed aperture, a supporting and centering pin carried by said handle for extending through said casing opening into supported cooperation in said axial aperture, and a threaded sleeve nut permanently rotatably attached to said handle and cooperating 65 with said driving member to hold the handle in operative position thereon.

7. In a machine of the character described, in combination, mechanism including a rotary driving member, a frame supporting said mechanism, a casing within which said frame and said driving

member are positioned, said casing having an opening adjacent to said driving member which latter is positioned wholly within the casing, an operating handle outside of said casing, attaching connections mounted on said handle and insertable through said casing opening for attaching the handle to said driving member for operation of the latter, a stub shaft mounted on said frame and having an axially disposed aperture, a supporting and centering pin carried by and coaxial with said handle for extending through said casing opening into supported cooperation in said axial aperture, a hub attached to said handle and having a peripheral groove and a threaded sleeve nut rotatably mounted on said hub and having a retaining flange positioned in said groove, said nut being threaded to said driving member to hold the handle in operative driving position thereon.

8. An operating handle for machines of the character described including, in combination, a hub having a groove, a supporting and centering pin carried by said hub and positioned coaxially with the handle, and a threaded sleeve nut rotatably mounted on and outside of said hub and having a retaining flange positioned in said groove.

9. In a machine of the character described, in combination, a rotary mechanism including a rotary driving member, an operating handle, interengaging lugs respectively connected to said driving member and to said handle, a guiding and supporting pin attached to said handle and coaxial therewith for guiding the latter into operative position and to hold it in such position, and an attaching device on said handle for attaching it in operative driving relation with said rotary driving member with said lugs in interengaging driving relation.

10. In a machine of the character described, in combination, a rotary mechanism including a rotary driving member, an operating handle, interengaging lugs respectively connected to said driving member and to said handle, a guiding and supporting pin attached to said handle and coaxially therewith for guiding the latter into operative position and to hold it in such position, said rotary driving member being threaded, and an attaching device rotatably connected to said handle and being threaded for connection to the threads of said driving member so as to hold the handle operatively connected to said driving member with said lugs in interengaging driving relation.

11. In a machine of the character described, in combination, a rotary mechanism including a rotary driving member having an apertured hub, a supporting stud engaging the aperture of said hub for rotatably mounting said driving member and also having an aperture, an operating handle, interengaging lugs on said handle and said driving member for transmitting driving energy to the latter, a guiding and supporting pin connected to and coaxial with said handle adapted to enter the aperture in said mounting stud, and an attaching device holding said lugs in interengaging driving relation and rotatably mounted on said handle and having threaded connection with said driving member.

12. In a machine of the character described, in combination, a frame in which rotary mechanism is mounted, a casing having an interior compartment in which said frame is received and housed in operative position, a rotary driving member for said mechanism wholly positioned

within said casing, an operating handle positioned outside of said casing, a guiding and supporting pin mounted upon and carried by said handle and coaxial therewith and extending into operative relation with said rotary driving member, and an attaching device holding said handle in coupled driving relation with said driving member and rotatably mounted on said handle and having threaded connection with said driving member.

10 13. An operating handle for machines of the

character described including, in combination, a hub having a groove, a supporting and centering pin carried by said hub and positioned coaxially with the handle, and a threaded sleeve nut rotatably mounted on said hub and having a retaining flange positioned in said groove, said sleeve nut being in telescopic relation outside of said hub and having its outer surface in juxtaposition to said hub for operative access.

WILLIAM A. PRINGLE.
